UNITED STATES PATENT OFFICE.

ANTONIO CERRUTI, OF SAN FRANCISCO, CALIFORNIA, ASSIGNOR TO CALIFORNIA FRUIT CANNERS ASSOCIATION, OF SAN FRANCISCO, CALIFORNIA, A CORPORATION OF CALIFORNIA.

EXHAUST-BOX FOR CANS.

1,068,565.

Specification of Letters Patent.

Patented July 29, 1913.

Application filed October 31, 1912. Serial No. 728,874.

To all whom it may concern:

Be it known that I, ANTONIO CERRUTI, a citizen of the United States, residing in the city and county of San Francisco and State 5 of California, have invented certain new and useful Improvements in Exhaust-Boxes for Cans, of which the following is a specification.

My invention relates, generally, to heating boxes used in the canning art, and while it is applicable to apparatus and devices for subjecting the cans to heat for cooking their contents, as such term is applied to the second of final cook, it is particularly adapted 15 for what is known as the first cook, that is, for applying sufficient heat to the still open but filled cans to expel the air prior to capping the cans, said apparatus being commonly called an exhaust-box.

10 The object of my invention is to provide a device of that type which employs a comparatively small and compact box occupying but little room on the floor, and in which the path of the cans is extensive enough to gain 15 the necessary time of subjection to the heat; and to improve said box by a novel course of the can-path which will result in economy 20 of heat.

Accordingly, my invention consists in the 30 novel heating or exhaust box which I shall now fully describe by reference to the accompanying drawings, in which—

Figure 1 is a vertical sectional view of my box taken on line $y-y$ of Fig. 2, many of 35 the interior parts, such as the can tracks, the cable guide, supporting members and the like, being omitted, for the sake of more clearly showing the course of the cable on the rising side, and thus indicating the path 40 of cans. Fig. 2 is a horizontal section of my box taken on line $x-x$ of Fig. 1. Fig. 3 is a horizontal section, enlarged, of one end 45 of Fig. 2, in order to more clearly show the communication of the rising with the descending can-path. Fig. 4 is a vertical section, enlarged and broken, of one end of the box, taken on the descending can-path side 50 of said box.

The box 1 may be of any suitable character. It is a closed, tight box with the exception of an entrance aperture or opening and an exit aperture or opening and both of these are in the lower portion of the box, in the ends thereof, the entrance open-

ing 2 being seen in Figs. 1 and 2, and the 55 exit opening 3 being seen in Figs. 2, 3 and 4. Within the box is a sheet metal lining 4.

5 are vertically disposed metal supports, preferably of channel section, as indicated in Figs. 2 and 3. These supports are arranged in two lines longitudinally of the box, three being here shown in each line. To these supports are secured the horizontal arms 6. These arms are on each side of each support 5, and are in vertical series 60 65 thereon.

Arranged within the box and at one side thereof is a series of reversely arranged inclined track sections extending from one end portion of the box to the other and alternately connected at opposite ends of the box to form a continuous way from the lower portion of the box to the upper portion thereof, and at the other side of the box is a series of reversely arranged inclined track 70 sections extending from one end portion of the box to the other and alternately connected at opposite ends of the box to form a continuous track descending from the upper portion of the box to the lower portion thereof. The track sections are made up of angle rails 7 arranged in pairs and supported upon the horizontal arms 6.

For a better understanding, it will be well at this point to describe the course of the 85 cable. It is a single endless cable.

Within the box are four vertical spindles 10, two at each end symmetrically disposed. Each spindle carries a vertical series of pulleys 11. Now by referring to Fig. 2, the cable 9, as indicated by the arrow, enters the box through the entrance opening 2 in the lower portion of said box. Turning now to Fig. 1, it will be seen that said cable passes the lowermost pulley 11 on one of the near spindles 10, and thence extends on a rising incline to the lowermost pulley on the corresponding spindle at the opposite end of the box; thence around said pulley and back again on a rising incline to the next pulley 100 above on the first spindle; thence around said pulley and to the far end again on a rising incline to the pulley next above on the far spindle and so on back and forth in rising inclines to the uppermost pulley on the far shaft. Now referring to Fig. 3 it will be seen that the cable passes directly over to the uppermost pulley on the adjacent spin-

idle at said far end, and thence back to the near end of the box but on a descending incline, as seen in Fig. 4, to the uppermost pulley on the corresponding spindle, at said 5 near end, and thence forth and back between said spindles on a descending incline until, as seen by Fig. 2, it passes to a drum 12 let into the entrance end of the box. It takes several turns about said drum, as in Fig. 13 1, and thence around a tightener pulley 13, (Fig. 2) and thence to a guide pulley 14 and to the point of beginning. It will now be seen that the cable rises within one side of the box and descends within the other side. 15 By its direction over its pulleys its forward course is to one side of and thereby clears its backward course. The several rails follow the cable course. The guides 8 for the cable follow it back and forth to the pulleys 23 11. The can track rails 7 likewise follow it to the pulleys 11 and there intimately approach curved end rails 15 by which the tracks are made continuous.

To enable the cans to cross over from the 25 top of the first can track to the top of the second can track, a track member 15' operates in conjunction with one of the curved rails 15, the curved rail 15 and the track member 15' being positioned on opposite 30 sides of the portion of the cable 9 which connects the two uppermost pulleys.

In operation the cans will be fed in close 35 succession to the entrance opening 2, and the can procession will thence move forward on the tracks 7 within the box, being advanced thereon by the mere contact of the traveling cable 9 with their bases. The cans will be carried forth and back in the box in a rising path from the lower portion of the box to 40 its upper portion, and then again back and forth in a descending path to the lower portion again, until they are delivered from the box through the exit opening 3. Any suitable means may be employed for heating the 45 box. I have in Figs. 2 and 3 indicated steam pipes or coils 30.

By having both the entrance and the exit 50 openings in the lower portion of the box, the upper portion thereof may be kept tight and thus confine and conserve the heat. The cans are carried up into a permanent region 55 of greatest heat and then brought down again and their course is sufficiently extensive to afford the necessary time for cooking, at the same time that the box is comparatively small and takes up but little room on the floor.

16 is the drive shaft with fast and loose 60 pulleys 17 and 18. The shaft 16 has the gear 19 which meshes with a gear 20 on a countershaft 21, which carries worms 22 meshing with worm gears 23 on the lower ends of the vertical spindles 10 which protrude through the bottom of the box. At the other end of 65 the box, 24 in Fig. 1 is a shaft which has at

one end a pinion 25 meshing with a pinion 26 on the protruding end of the spindle 10. The other end of the shaft 24 has a pinion 27 meshing with a pinion 28 on a vertical countershaft 29 which carries the guide pulley 14 at its top, so that said pulley is also a driver. 70

I claim:—

1. In an exhaust box for cans the combination of a box, means for heating said box, a series of reversely arranged inclined track sections in the chamber extending from one end portion thereof to the other and alternately connected at opposite ends of the chamber to form a continuous track from the lower portion of the box to the upper portion thereof, a can track portion connecting with the upper end of the first mentioned track and forming a continuation of the same extending downwardly therefrom to the lower portion of the box, and means for progressing the cans upon the track. 80

2. In an exhaust box for cans the combination of a box closed in its upper portion and provided in its lower portion with an entrance and an exit for the cans, a series of reversely arranged inclined track sections in the chamber extending from one end portion thereof to the other and alternately connected at opposite ends of the chamber to form a continuous track from the lower portion of the box to the upper portion thereof, a can track portion connecting with the upper end of the first mentioned track and forming a continuation of the same extending downwardly therefrom to the lower portion of the box, one end of said can track being in communication with the entrance to the box and the other end of said track being in communication with the exit from the box, and means for moving the cans along the tracks. 100

3. In an exhaust box for cans the combination of a box closed in its upper portion and provided in its lower portion with an entrance and an exit for the cans, means for heating said box, a series of reversely arranged inclined track sections in the chamber extending from one end portion thereof to the other and alternately connected at opposite ends of the chamber to form a continuous track from the lower portion of the box to the upper portion thereof, another series of reversely arranged inclined track sections in the chamber extending from one end portion thereof to the other and alternately connected at opposite ends of the chamber to form a continuous track descending from the upper portion of the box to the lower portion thereof, a track section connecting the upper portion of the first mentioned track with the upper portion of the last mentioned track, the lower end of said first mentioned track communicating with the entrance to the box and the lower 120 110 115 125 130

end of the second mentioned track communicating with the exit from the box, and means for progressing the cans upon the tracks.

4. In an exhaust-box for cans, the combination of a box, closed in its upper portion and provided in its lower portion with an entrance and an exit for the cans; means for heating said box; a can track communicating at its lower end with the entrance to the box and thence extending in a continuous course forth and back within the box and rising therein from the lower portion to the upper portion of the box; a second can track connecting at its upper end with the upper end of the first can track and thence extending in a continuous course forth and back within the box and descending therein from its upper to its lower portion and communicating at its lower end with the exit from the box; and a means for progressing the cans upon said tracks from the entrance to the exit, consisting of an endless traveling cable contacting with cans and arranged between the can-tracks, said cable crossing over from the upper end of the ascending tracks to the adjacent upper end of the descending tracks.

5. In an exhaust box for cans, the combination of a box, means for heating said box, a can track comprising separated rails extending in a continuous course back and forth within the box and rising therein from the lower portion to the upper portion of the box, a series of horizontally disposed portions supported in said box at the bends in said track and positioned in the plane of the track to form a part thereof, and means for progressing cans upon the track comprising pulleys supported within the box and an endless traveling cable supported

upon said pulleys and positioned between the rails of the can track so as to contact with the cans supported thereby.

6. In an exhaust box for cans the combination of a box closed in its upper portion and provided in its lower portion with an entrance and an exit for the cans; means for heating said box, a series of reversely arranged inclined track sections in the chamber extending from one end portion thereof to the other and alternately connected at opposite ends of the chamber to form a continuous track from the lower portion of the box to the upper portion thereof, another series of reversely arranged inclined track sections in the chamber extending from one end portion thereof to the other and alternately connected at opposite ends of the chamber to form a continuous track descending from the upper portion of the box to the lower portion thereof, a track section connecting the upper portion of the first mentioned track with the upper portion of the last mentioned track, the lower end of said first mentioned track communicating with the entrance to the box and the lower end of the second mentioned track communicating with the exit from the box, and a conveyor provided with sets of reversely inclined flights corresponding to the sets of inclined track sections extending along the same and progressing the cans upon the tracks.

In testimony whereof I have signed my name to this specification in the presence of two subscribing witnesses.

ANTONIO CERRUTI.
